UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN

DIPPER STICK

Application filed June 9, 1926. Serial No. 114,832.

The present invention relates in general to excavating or shoveling machines of that type which are power driven and include a dipper carried by the swinging end of a dipper stick, and among the objects of the invention are to provide a dipper stick which embodies novel features of construction, whereby it is flexible and will yield in certain directions to facilitate the operation of the machine and prevent excessive stresses.

In the operation of power driven excavating machines it sometimes happens that when the dipper is swung laterally its side swipes the top of the bank or encounters some obstruction, with the result that very heavy strains and stresses are produced in the connection between the inner end of the boom and the machine. Owing to the fact that any lateral force acting on the dipper has a very powerful leverage on the parts connecting the boom to the machine, the stresses produced in such parts are very great and breakage is liable to happen therein. According to the present invention the dipper arm is constructed so that it is flexible to a certain extent in a lateral direction and will operate as a shock absorber and reduce the stresses to such an extent that the danger of breakage may be partially or completely eliminated.

While certain particular embodiments of the invention are shown and described for illustrative purposes, it will be understood that many modifications and changes can be made in the design, proportions and details of construction without departing from the spirit of the invention.

For a full understanding of the invention reference is to be had to the following description and accompanying drawings in which,

Figure 1 is a plan view of one form of dipper arm which is constructed in accordance with the invention, the normal position thereof being shown by full lines, and one of the positions assumed when the arm is flexed being shown by dotted lines.

Figure 2 is an enlarged transverse sectional view taken on the line 2—2 of Figure 1.

Figure 3 is a sectional view through one side of a modified construction of the dipper arm, showing a portion of the gearing between the dipper arm and dipper shaft.

Figure 4 is a plan view showing another modified construction of the flexible dipper arm.

Figure 5 is an enlarged transverse sectional view taken on the line 5—5 of Figure 4.

Figure 6 is a top plan view of a modified form of the invention in which the dipper stick comprises a single laminated arm.

Figure 7 is an enlarged transverse sectional view through a single arm laminated dipper stick showing a shipper shaft assembly for a cable drive.

Figure 8 is a similar view showing a shipper shaft assembly for a rack and pinion drive.

Corresponding and like parts are referred to in the following description and indicated on all of the views of the drawings by like reference characters.

Referring to Figures 1 and 2 of the drawings, the reference character A designates two half sections of the dipper stick which is of the bifurcated pattern and adapted to straddle a boom member. Each of the dipper stick sections A is shown as comprising a main plate 1 and progressively shorter plates 2 and 3 which are appropriately secured to the plate 1 by means of suitable shackles 4. The plates 1 are suitably fastened to the dipper 5 and, for illustrative purposes, this is shown as accomplished by riveting the ends of the plates 1 to lugs 6 which project rearwardly from the dipper.

At the other end of the dipper stick the several component plates or elements 1, 2 and 3 of each section A thereof are securely fastened together in some suitable manner as by means of the bolts 7. The plates 1, 2 and 3 are superposed on each other and have their longer dimensions arranged substantially in vertical planes so that the dipper is held rigidly against up and down movement, but can flex or yield laterally.

The main element or leaf 1 of each dipper section A may be thicker and heavier than

the shorter plates or leaf members 2 and 3, as shown more clearly by Figure 2. The elements or plates 1 may also be wider than the plates 2 and 3, so that the bolts 4^a of the shackle members 4 may pass through edge portions of the plates 1, as shown by Figure 2. This leaves the inner face of each section A of the dipper stick free and clear of obstructions, and also anchors the shackle members in position so that they are prevented from creeping. The sections A of the dipper stick have a spaced and parallel relation and are assembled with the shorter plates 2 and 3 on the outer side 15 of each of the main plates 1. The two sections A are slidably engaged on their inner faces by saddle block members 8. These saddle blocks are keyed to a shipper shaft which is journaled in a suitable bearing 9 20 on a boom 10, said boom being indicated by dotted lines on Figure 1. Any suitable form of crowding mechanism may be employed, although with the construction which has just been described, a cable racking 25 and crowding means would probably be preferable. The dipper stick is thus mounted so that it can have the usual longitudinal movement, and will be operated in the usual manner, although the construction thereof 30 is such that it can flex or yield laterally when an obstruction is encountered upon a lateral movement of the dipper, thereby enabling the dipper stick to act as a shock absorber and prevent excessive strains accompanied 35 by a possible breakage at the inner end of the boom.

A modification is shown by Figure 3 in which each section A of the bifurcated dipper stick comprises a main plate or leaf element 11 with a plurality of smaller plate or leaf elements 12 on each side thereof, said plates or leaf members being held together by shackles 13. One edge of the main plate or leaf member 11 is formed with 40 a rack which engages a pinion 14 on the shipper shaft 15. The opposite edge of the main plate or leaf member 11 is slidably engaged by another form of saddle block 16 which serves to direct the dipper stick in 45 its sliding movements and hold the rack in operative engagement with the pinion. This form of dipper stick is adapted to flex laterally to absorb sudden shocks and jars when an obstruction is encountered by the dipper. 50

A further modification is shown by Figures 4 and 5, in which each section A of the dipper stick includes a plurality of wide plates or leaf members 17 and a plurality of comparatively narrow plates or leaf members 18, said plates or leaf members being assembled in a side by side relation and held together by suitable shackles 19. One end of each of the sections A is pivotally connected to the dipper 5 in some suitable man-

ner as indicated at 20. The plates or leaf members are arranged in substantially vertical planes so that the dipper is held rigidly against vertical movement relative to the dipper arm, but can flex laterally. The sections A of the dipper stick may be slidably engaged by saddle block members 8 on a shipper shaft 21, as shown on the drawings. The pivotal connections between the dipper stick sections and the dipper enable the dipper stick to flex laterally without producing a relative longitudinal movement of the sections A, which movement might be objectionable if certain forms of gearing were used for operating the dipper stick. In all of the forms of the invention the dipper stick is constructed so that it can flex laterally and absorb sudden shocks and jars such as those which are caused when the dipper is being swung laterally and side swipes the top of the bank or meets an obstruction. 85

Figures 6, 7 and 8 illustrate a still further modification in which the dipper stick comprises a single laminated arm. As shown by Figures 6, 7 and 8 this dipper stick comprises a central plate 22 which is provided at each side thereof with the progressively shorter plates 23 and 24. The side plates 23 and 24, as is shown more clearly by Figures 7 and 8, are preferably narrower than the main plate 22, so that the longitudinal edges of the main plate project beyond the edges of the side plates. Suitable shackles 25 are employed to hold the side plates in position, and these shackles may be conveniently fastened by bolts 26 or like members which extend through the projecting edge portions of the main plate and connect the shackle members on opposite sides thereof. The end of the main plate 22 is shown as rigidly secured at 27 to the dipper 5. 100

On Figure 7 is shown a shipper shaft assembly which is adapted for a cable drive. The shipper shaft 28 is suitably journaled on the boom 29 and provided at its middle portion with a grooved guide wheel 30 which engages one of the edge portions of the main plate 22. The opposite edge portion of the main plate of the dipper stick is 115 slidably engaged by a suitable saddle block 31 so that the dipper stick is effectively guided during its in and out movements.

Figure 8 shows a shipper shaft assembly which is designed for a rack and pinion drive. The shipper shaft 28 is suitably journaled upon the boom 29 as in the previous instance. The middle portion of the shipper shaft is provided with a pinion 32 which meshes with a rack 33 on the edge of the main plate of the dipper stick. This rack is shown as provided at the sides thereof with guide flanges which straddle the pinion and prevent lateral displacement of the rack upon the pinion. The opposite 130

edge of the main plate of the dipper stick is slidably engaged by a suitable saddle block 34. The dipper stick is thus effectively guided in its back and forth movements 5 and adapted to be propelled by the cooperation of the rack and pinion.

This single arm dipper stick is, of course, constructed so that it will flex or yield laterally when an obstruction is encountered 10 upon a lateral movement of the dipper, thereby enabling the dipper stick to act as a shock absorber and tend to prevent the dangerous and excessive strains which are produced in the parts at the inner end of 15 the boom under such circumstances.

The present invention is characterized by the capacity of the dipper stick to flex without injury to itself, and without injury to the parts cooperating with it. To this end, 20 the stick is essentially formed of spring-leaf construction, preferably of the flat or plate spring type, and as a further specific detail also, by preference, having leaf springs of progressively increasing or varying 25 lengths.

Having thus described my invention what I claim as new and desire to secure by Letters Patent is:

1. In excavating machines, a dipper, a 30 laminated dipper stick having the laminae on one side thereof narrowing down in width dimension, and shackles engaging about the laminae for holding the laminae together, said shackles including bolts which pass 35 through the edge portions of a lamina only.

2. In excavating machines, a dipper, and a laminated dipper stick section including a main plate and auxiliary side plates, the side plates being narrower than the main 40 plate and one of the projecting edges of the main plate being formed with a rack independent of the side plates.

3. In an excavating machine, a dipper, and a stick composed of a pair of spaced 45 members and a shiftable connection intermediate the spaced members and the respective sides of the dipper, permitting relative movement of the members while maintaining the normal relative position of the dipper.

4. In an excavating machine, a dipper, and a dipper stick composed of spaced parallel side members yieldable laterally under 55 force of side impacts, and pivot connections intermediate said members and the dipper extending in a vertical plane whereby the dipper is maintained in its normal relative excavating position during the lateral yielding aforesaid.

5. In an excavating machine, a dipper, and a dipper stick therefor composed of a pair of spaced side members hingedly connected to the dipper, the hinged connections 65 extending in parallel vertical planes to per-

mit lateral shifting of the dipper relative to the side members.

6. In an excavating machine, a dipper, a flexible dipper stick therefor, composed of spaced side members, each of which is flexible, and a shiftable connection between the 70 side members and the dipper.

7. In an excavating machine, a dipper, a flexible dipper stick therefor composed of spaced side members each of which is flexible in a direction transverse to the direction 75 of load stresses, and pivotal connections between the dipper stick side members and the dipper axially disposed in a direction transverse to that in which the side members may flex.

In testimony whereof I affix my signature.

ERICH H. LICHTENBERG.
